By Attorney.

UNITED STATES PATENT OFFICE

ABRAHAM CARO, OF DORCHESTER, MASSACHUSETTS, ASSIGNOR TO THE HORTON & HUBBARD MFG. CO., OF EAST SOMERVILLE, MASSACHUSETTS, A CORPORATION OF MAINE

POCKET REST

Application filed October 26, 1928. Serial No. 315,145.

The device of the present invention is a support or rest for the hinged pocket flap or cover of a suitcase, trunk, or like article of baggage when the flap or cover is closed over the pocket and functions to prevent the free edge of the flap or cover from swinging down into the pocket in its closing movement as well as providing a convenient mount for a fastening tab by means of which the flap or cover may be fastened in its closed position. As such, it is therefore an article of dual function serving both as a stop or rest for the hinged flap or cover when closed and a convenient anchorage for the flap fastening tab.

The construction and operation of my device is described and illustrated in the accompanying specification and drawing and the particular features of novelty are pointed out in the appended claims.

In the drawings:—

Fig. 1 is a fragmentary section through a suitcase or similar article of luggage equipped with a device in accordance with my invention.

Fig. 2 is a partial plan view of Fig. 1, the pocket covering flap being shown in closed position.

Fig. 3 is an enlarged detail section through one of my cover rests.

Fig. 4 is an enlarged face view thereof, and

Figs. 5 and 6 are detached perspective views thereof.

For the purposes of this application, I have shown my invention in its adaptation to a suitcase of the type wherein a pocket or compartment 1 is formed in its hinged cover section 2, the body of the suitcase being fragmentarily indicated at 3, and the hinged pocket cover or flap at 4. This illustration, however, is purely for purposes of disclosure and in no way limiting, as it will be understood that the principles of my invention may be applied to any article of luggage wherein a pocket is provided in the article which ar-

title is adapted to be covered by a hinged flap or closure.

The flap or cover 4 is hinged as by a flexible hinge 5 to the inner wall 6 of the pocket forming portion of the article of luggage and is supported at its free end by one or more rests 7 mounted on the inner face of the outer wall 8 of the pocket forming member. In the illustrative embodiment shown, the walls 6 and 8 are the longitudinal walls of the cover member 2 of the suitcase and the rests 7, of which two are shown in these drawings, serve as stops to prevent the flap 4, when closed, from swinging down into the pocket itself.

Each rest 7 is formed as a relatively elongated attaching portion 9 of generally channeled form terminating at its upper end in an inwardly extending horizontally disposed rest portion 10 which functions as a stop for the free edge of the flap 4. Preferably, the lateral edges 11 of the attaching portion 9 are provided with one or more barbs 12 which are adapted to be driven into the material of the wall 8 thereby to fix the rest 7 to the wall.

The channeled construction of the rest 7 provides with the wall 8 a vertically disposed recess indicated generally at 13 for the reception of a flap fastening tab 14. The tab 14 is fastened in said recess 13 and to the wall 8 by the rivet 15 which rivet also assists in anchoring the rest 7 to the wall 8. The free end of the tab 14 may be provided with any suitable socket fastener 16 adapted to engage a stud 17 carried by the upper face of the flap 4 whereby detachably to fasten the flap 4 in closed position as appears in Fig. 2.

By this construction, the flap is not only prevented from swinging down into the pocket when closed, but the stops or rests for the flap also serve as a convenient means for mounting the fastening tabs 14 for the flap on the wall 8.

Various structural modifications may obvi-

ously be resorted to within the spirit and scope of my invention as defined by the appended claims.

What I therefore claim and desire to secure by Letters Patent is:

- 5 1. A device of the class described adapted for use with an article of baggage having a pocket and a movable closure for said pocket, comprising a member mounted on one of the 10 pocket-defining walls of the article of baggage and presenting a stop portion disposed in interfering relation to the free edge of the pocket closure when said closure is moved to closed position, said member shaped to provide with the pocket-defining wall on which it is mounted an open-ended recess, and a fastening tab anchored in said recess at one end and provided at its free end with means adapted for quick detachable connection with 15 the pocket closure when closed whereby to permit said closure to be detachably fastened in closed position.
- 20 2. A device adapted for use with an article of luggage having a pocket and a cover movable relative to said pocket, comprising a member mounted on the inner face of one of the pocket defining walls and presenting an offset stop or rest disposed in interfering relation to the free edge of the pocket cover when said 25 cover is moved to closed position, said member being of channeled form and defining with the pocket forming wall on which it is mounted an open-ended recess, and a fastening tab anchored in said recess and provided 30 in its free end with means adapted for quick detachable engagement with the pocket cover when closed whereby to permit said cover to be detachably fastened in closed position.
- 35 3. A device adapted for use with an article 40 of luggage having a pocket and a cover movable relative to said pocket, comprising a vertically disposed member mounted on the inner face of one of the pocket defining walls and presenting an inwardly extending substantially horizontally disposed stop or rest for 45 the free edge of the pocket cover when said cover is moved to closed position, said member being of channeled form and defining with the pocket forming wall on which it is 50 mounted a vertically disposed recess, and a fastening tab anchored in said recess and provided in its free end with means adapted for quick detachable engagement with the pocket cover when closed whereby to permit said 55 cover to be detachably fastened in closed position.
- 60 4. A device adapted for use with an article of luggage having a pocket and a cover movable relative to said pocket, comprising a vertically disposed member mounted on the inner face of one of the pocket defining walls and presenting an inwardly extending substantially horizontally disposed stop or rest for 65 the free edge of the pocket cover when said cover is moved to closed position, said mem-

ber being of channeled form and provided with one or more barbs along its lateral edges by means of which it may be anchored to the wall of the pocket and defining with such wall a vertically disposed recess, and a fastening tab anchored in said recess and provided in its free end with means adapted for quick detachable engagement with the pocket cover when closed whereby to permit said cover to be detachably fastened in closed position.

In testimony whereof I affix my signature.

ABRAHAM CARO.
